UNITED STATES PATENT OFFICE.

JOHN K. THOMAS, OF COLUMBUS, OHIO.

VAPOR-BURNING COOKING-STOVE.

SPECIFICATION forming part of Letters Patent No. 271,158, dated January 23, 1883.

Application filed July 5, 1882. (No model.)

To all whom it may concern:

Be it known that I, JOHN K. THOMAS, a citizen of the United States, residing at Columbus, in the county of Franklin and State 5 of Ohio, have invented new and useful Improvements in Vapor-Burning Cooking-Stoves, of which the following is a specification.

My improvement consists of a device placed upon the table-top of a vapor or hydrocarbon-10 gas stove for intensifying and equalizing the heat of the burner. The device is specially adapted for use with vapor-burning stoves now in use, having a table-top with openings above the burners provided with spiders for the support of the cooking-vessel, leaving an unobstructed central space within the spider for the direct action of the flame upon the vessel or oven, but is equally well adapted for use with a stove-top without spider-supports for the 15 cooking-vessels. The device consists of a flat heat-retaining chamber, the bottom ring-plate whereof rests upon the top-plate of the stove, while the top ring-plate of the heat-retaining chamber forms the support for the cooking-vessel. The bottom ring-plate of the device 20 has a central opening and a depending collar surrounding the burner, and the top ring-plate has a central deflector and an annular opening, so that the flame from the burner entering the space between the ring-plates is deflected into the annular opening and partially into the chamber formed by the top and bottom ring-plates; thus retaining the heat with an intensifying and equalizing action upon the vessel 25 supported upon the top plate. To give full effect to the contact of the flame upon the bottom of the oven or cooking-vessel the top ring-plate is provided with cross-rods or surface projections, upon which the cooking utensil 30 rests to raise its bottom above the flat surface of the stove-top.

Referring to the accompanying drawings, Figure 1 represents a vertical section of a part of the stove-top plate and an elevation of so 45 much of the burner of a vapor-burning stove as shows the application of the heat intensifying and equalizing device thereto, and Fig. 2 a view in perspective of the flat-chambered device which constitutes my improvement.

50 The stove is of the style in which a table-top, *a*, supported by legs, is provided with open-

ings for two or more burners, *b*, suitably supported below said table-top. In stoves of this style now in use such openings are provided with spiders *c* for supporting the cooking-vessel and for the diffusion of the flame against its bottom. My improvement is adapted for use with such a stove, with or without the spider-support—that is, it takes the place of the spider-support, but may be used with it—55 and when so used, as shown in the drawings, the spider-support is without function.

The device which I have designed to take the place of the spider is composed of two ring-plates, *d* and *e*, joined at their circumference by lapping ring-bands *f*, about an inch and a half wide, the ring-plates being about ten inches in diameter and forming a heat-retaining chamber. The bottom ring-plate, *d*, has a central opening and a depending collar, *g*, adapted to fit over the burner and to leave a surrounding space for supplying it with air. The top ring-plate, *e*, has a central deflector, *h*, connected with it by radial arms *i*, and an annular opening, *j*, about an inch and a half, 60 separates the said central deflector from the inner edge of the said top ring-plate and forms the issuing opening for the flame from the chamber. The bottom ring-plate lies flat upon the table-top spiders of the stove, and the collar *g* directs the flame into the chamber, so that striking the central deflector it spreads out 65 into the annular space and partially into the chamber, which, retaining the heat, intensifies and equalizes it upon the oven or vessel which 70 is supported upon the top ring-plate. The flat surface of the top ring-plate is separated from the bottom of the cooking-vessel by means of cross-rods *k*, preferably of copper, clinched in 75 said plate, whereby the flame is allowed to spread under the vessel as well as under the top ring-plate. Surface projections will answer this purpose, but the copper rods, which 80 may be arranged in any suitable manner, are preferred because they increase the heating 85 capacity of the heat-retaining chamber. Any 90 suitable number of copper rods may be used for this purpose, and they may be arranged in rings and cross-strands both upon the surface of the ring-plate and of the central plate deflector, but not over the annular flame-space. 95 It will be understood that the flame-directing 100

collar projects through an opening in the table-top or through a central opening in the spider.

The device is made of sheet-iron, and in order to provide for cleaning the chamber of the product of the flame each ring-plate is provided with a separate ring-band of equal width, lapping and fitting each other closely, so that they can be separated, when required, as shown in Fig. 3.

I claim—

1. The combination, in a vapor-burning stove, of the table-top provided with openings and centrally-arranged burners, with the flat-chambered device, herein described, consisting of a bottom ring-plate, *d*, having a collar, *g*, a top ring-plate, *e*, having a central deflector, *h*, and an annular opening, *j*, and circumferential ring-bands *f*, joining said ring-plates, forming a heat-

retaining chamber, substantially as described, 20 for the purpose specified.

2. The vessel or oven support for vapor-burning stoves herein described, consisting of top and bottom ring plates, *e d*, joined by closely-fitting lapping circumferential ring-bands *f*, the bottom ring-plate being provided with a central opening and a depending collar, *g*, and the top ring-plate having a central deflector, *h*, an annular opening, *j*, and surface rods or projections *k*, substantially as described, 30 for the purpose specified.

In testimony whereof I have hereunto set my hand in the presence of two subscribing witnesses.

JOHN K. THOMAS.
